HEAT DETECTION DEVICE

John Evans, Kingston, N. J., assignor to Radio Corporation of America, a corporation of Delaware

Application December 20, 1943, Serial No. 515,058

15 Claims. (Cl. 201—63)

1

This invention relates to heat detecting devices and especially to a heat detecting device including a plurality of separately responsive units adapted to respond to a plurality of heat sources at the same or at different temperatures.

Numerous heat detecting devices have been disclosed in the prior art. Many of these devices are in the form of cells which are not especially sensitive. Some cells may have the required sensitivity but their response is sluggish and they are not suitable when rapid response is required. In many systems sluggish response may be tolerated but in systems for forming an image of a scene by scanning the radiations therefrom, a rapid response is required if the image is to be formed rapidly. Moreover, if good resolution is required, the image must be made up of a large number of elements, and a large number of elements correspond to a large number of heat responsive cells, which would be grouped to form a mosaic. While a large number of the prior art devices may be combined to form a mosaic, the design and manufacturing difficulties become more apparent by assuming that a suitable image would include not less than say 100 lines or 10,000 elements.

According to an object of the present invention there is provided an improved heat responsive cell in which rapid response and increased sensitivity are secured. Another object is to provide an improved heat responsive device including a plurality of separate heat responsive units. An additional object is to provide an improved method for manufacturing multi-unit heat responsive devices suitable for scanning systems. A further object is to provide an improved heat responsive device in which a plurality of heat responsive elements are linearly arranged.

The invention will be described by referring to the accompanying drawings in which Figure 1 is an elevational view of an assembled heat responsive device according to a preferred embodiment of the invention; Figure 2 is a sectional view taken along the line II—II of Figure 1; Figure 3 is an elevational view taken along the line III—III of Figure 2; Figure 4 is a sectional view taken along the line IV—IV of Figure 3; Figure 5 is a sectional view of a portion of the heat responsive units; and Figure 6 is circuit diagram including the heat responsive unit of the invention. Similar reference characters indicate similar elements in the drawings.

Referring to the drawings, a metal supporting plate 1 is mounted on a case 3 which surrounds the heat responsive device 5. The sup-

2

porting plate includes an aperture 7, which may be surrounded by a grommet 9. The grommet may include a heat transparent window (not shown). Suitably disposed behind the aperture 7 is membrane 11 which is hereinafter described. The membrane is stretched tightly over an insulated support 13. The support may be made of a synthetic resinous material, such as "Lucite." The insulated support 13 may include a metal backing plate 15. The insulated support 13 is spaced from the metal support 1 by insulated spacing strips 17, 19. One of these spacing strips 17 includes a common conductor 21; the other spacing strip 19 includes a plurality of conductors 23 which engage conductors connected to the separate units 25 of the heat responsive means 5.

The membrane 11 may be composed of cellulose acetate with suitable plasticizer and hardening agents. By way of example, a liquid of the following ingredients may be composed of the approximate amounts as indicated:

Pear oil	cc	50
Pure cellulose	gram	1
Formaldehyde	cc	.01
Chrome alum	gram	1
Synthetic camphor (Dupont)	do	.25
Glycerine	cc	.01

The ingredients are dissolved in the above sequence. A few drops of the thus prepared liquid may be poured upon water and left to solidify to form a membrane having a thickness of several microns, for example, 3×10^{-8} centimeters. Since the membrane is very delicate, it may be best lifted from the water by inserting a hollow rectangular frame under the membrane. Instead of lifting the membrane from the water, the support 13 may be inserted in the water before the liquid is poured on the surface of the water and after the membrane has formed the water level is lowered until the membrane rests on the support 13. If the frame method is employed and if the frame encloses an area appreciably larger than the support 13, the membrane may be deposited upon the support and will be secured thereto by molecular bonding, provided the surface of the support 13 has been polished. After the membrane is fastened securely the surplus may be trimmed by tearing or by dissolving the excess. The membrane after drying exhibits a very low thermal storage capacity, which is necessary if rapid response is desired.

The next step in preparing the heat responsive units is to cover the membrane with a mask.

The mask includes rectangular apertures corresponding to the heat responsive units 25. The mask may include three sets of positioning pins which are a snug fit in the holes 27 of the insulating support 13. The mask is first disposed in one position, say to the left of the center of the membrane and then the assembly is inserted into a suitable bell jar. The bell jar includes tungsten baskets, which are provided with heaters and gold to be evaporated. The bell jar is then evacuated to a "hard vacuum," i. e., 10^{-5} to 10^{-6} millimeters of pressure. Thereafter the baskets are heated and the gold is evaporated and is deposited on the portions of the membrane exposed by the apertures in the mask to form a 15 row of gold contacts.

The assembly is then removed from the bell jar, and the mask positioned to the right of the center of the membrane. The gold evaporating process as previously described is repeated thereby to deposit a second row of gold contacts. The assembly is again removed from the bell jar and the mask is centrally disposed with respect to the membrane.

The assembly with the mask centrally disposed is inserted in the bell jar in which tungsten baskets containing metallic tellurium have been placed. The bell jar is exhausted until a hard vacuum is obtained. A small amount of oxygen is permitted to enter the bell jar by heating a side tube which contains mercuric oxide. The heated mercuric oxide gives up oxygen to establish an oxygen atmosphere within the bell jar. When the tellurium is evaporated in the oxygen atmosphere, the tellurium molecules combine with the oxygen molecules. The combination is deposited on the membrane through the apertured portions of the mask, forming a "semiconductor" between each of the gold contacts. The semi-conductor, tellurium oxide which forms the heat responsive unit 25, has a negative thermal coefficient of resistance of large magnitude as compared with pure metals.

The gold contacts to the left of the heat responsive tellurium oxide elements 25 are connected to a common conductor 21 as described previously. The contacts to the right of the heat responsive elements are connected to separate external conductors by means of a multi-element contact bar which may be made as follows: An insulating strip 28 (see Fig. 5) of the required length and of suitable cross section is wound with wire 31 of a diameter preferably slightly smaller than the gold contacts. The turns of the wire may be spaced by a notched plate. The several turns are made of the desired length by a jig which positions the notched plate and the insulating strip. The strip, after the wires are in place, is wetted by means of a solvent. The wetted strip is clamped so that the wires are embedded in the wetted strip. The solvent on the strip is then allowed to harden so that the wires are securely positioned. The turns 23 may be cut along one edge of the strip to form a plurality of wires each having ends embedded in the strip. The embedded ends are then sandpapered or otherwise scraped to remove the insulation whereby good electrical contacts will be made when the strip is positioned as shown in Fig. 5. Thus the heat responsive units are connected to a common lead and to separate leads.

One suitable circuit including the heat responsive unit is shown in Figure 6. A battery 33 is connected through a series resistor 35 to a heat

responsive unit which is represented as a resistor 37. A meter 39 is connected across the heat responsive unit 37. A capacitor 41 may be included in series with the meter or the capacitor may be short circuited by a switch 43. A scanning disk or shutter 45, driven by a motor 47, may be arranged in front of the heat responsive element to scan or to interrupt the heat from a source not shown.

The modes of operation are as follows: First, if the capacitor is short circuited and the disk or shutter is not used to interrupt the heat, the heat falling on the heat responsive element 37 decreases the electrical resistance of the element because of its negative coefficient. If the resistance is lowered, more current will flow from the battery and hence a greater voltage drop will be indicated by the meter 39. Second, if the capacitor 41 is not short circuited and if the shutter is used to interrupt the heat which is applied to the heat responsive unit, the resistance of the unit 37 will increase and decrease at the rate of the interruptions. Thus, the current flowing through the unit 37 will increase and decrease and the voltage across the unit will vary. The magnitude of the varying voltage will be indicated on the meter 39. The magnitude of the varying voltage will be a measure of the temperature of the applied heat. Third, if the scanning disc is used with a plurality of units, heat may be applied separately to the several units of a multi-unit heat detector. Those units may be connected to separate indicators or the output may be used to form an image of the heat source as disclosed and claimed in copending application Serial No. 515,879, filed December 28, 1943, entitled Systems for forming images of heat radiating objects, Patent No. 2,403,066, and assigned to the same assignee as the instant application.

Thus the invention has been described as an improved heat responsive unit consisting of a very thin membrane of very low thermal capacity on which tellurium oxide is deposited. The oxide exhibits a negative resistance coefficient when heat is applied. While tellurium oxide is a preferred material, other semi-conductors or conductors or alloys of materials may be used, such as tellurium silver alloy composed of the order of 10 percent silver and 90 percent tellurium. A simple method has been described for forming a plurality of separate heat responsive units which are deposited on a common membrane. The heat responsive devices may be used to indicate heat which is applied steadily or intermittently to one or to more than one unit.

I claim as my invention:

1. A heat detector including a stretched membrane of low thermal capacity, a semi-conductor having a high coefficient of resistance attached to one side of said membrane, and a pair of conductors connected to said semi-conductor.

2. A heat detector including an electrically insulated stretched membrane, a semi-conductor having a high coefficient of resistance deposited on one side of said membrane, and a pair of conductors engaging said semi-conductor.

3. A heat detector including in combination an electrically insulated stretched membrane of low thermal capacity, a semi-conductive material having a negative coefficient of resistance attached to one side of said membrane and arranged to contact a pair of conductors.

4. A heat detector including an electrically insulated stretched membrane of low thermal capacity, a pair of electrical conductors deposited

upon one side of said membrane, and a semi-conductor having a negative coefficient of resistance connected between said pair of conductors.

5. A heat detector including a cellulose acetate membrane, a pair of electrical conductors deposited thereon, and a semi-conductor of tellurium oxide connected between said conductors.

6. A heat detector including a cellulose acetate membrane, a pair of electrical conductors deposited thereon, and a semi-conductor of tellurium oxide deposited upon said membrane and connected between said conductors.

7. A heat detector including a flexible plastic membrane a supporting member for said membrane, at least a pair of conductors deposited on said membrane, and tellurium oxide heat responsive units connected between said conductors.

8. The method of forming a heat responsive detector on a stretched membrane of low thermal capacity having a thickness of the order of 3×10^{-8} cm, which includes the steps of depositing on one side of said membrane a pair of conductors, and depositing between said conductors a semi-conductor having a negative coefficient of resistance.

9. The method of forming heat responsive units on a membrane which consists in masking portions of said membrane, placing said masked membrane within a vacuum, disposing within said vacuum a conductor, heating said conductor to deposit conductive portions on the unmasked portions of said membrane, arranging said mask to expose portions of said membrane between said conductive portions, placing the thus masked membrane within a vacuum, and heating tellurium within said vacuum to deposit tellurium on the exposed portions of said membrane.

10. The method set forth in claim 9 plus the additional step of supplying oxygen to said vacuum so that the tellurium deposit is oxidized.

11. A heat detector including a stretched membrane of low thermal capacity, and a semi-conductor deposited on one side of said membrane, said semi-conductor consisting of a material having a negative coefficient of resistance as a function of temperature.

12. A heat detector including a stretched membrane of low thermal capacity, and a negative thermal coefficient semi-conductor deposited on one side of said membrane.

13. A heat detector including a stretched membrane of low thermal capacity, a pair of conductors deposited on one side of said membrane, and a metallic oxide coated on said membrane between and connecting said conductors.

14. A heat detector including a stretched membrane of low thermal capacity, a pair of conductors deposited on one side of said membrane, and a material having a high thermal coefficient of resistance coated on said membrane between and connecting said conductors.

15. A heat detector comprising an electrically insulating support, a membrane stretched over said support and supported so as to have a suspended central portion, a thin layer of a metallic oxide having a relatively high coefficient of resistance deposited on said membrane and means for establishing electrical connections to spaced portions of said layer.
